ELECTRON TUBE STRUCTURE

Donald F. Drieschman, Los Altos, and Hubert H. Eaves, Palo Alto, Calif., assignors to Eitel-McCullough, Inc., San Bruno, Calif., a corporation of California

Application July 12, 1949, Serial No. 104,198

12 Claims. (Cl. 313—252)

1
Our invention relates to improvements in the construction of negative-grid type electron tubes, and more particularly, to power tetrodes.

It is among the objects of our invention to provide an improved tetrode for transmitting application such as modulator service.

Another object is to provide an electron tube of rugged construction, capable of withstanding heavy shocks without displacement of the electrodes.

A further object is to provide a tube with a simplified base structure and improved electrode supports.

A still further object is to provide an improved envelope construction and sealing arrangement for enclosing the electrodes.

The invention possesses other objects and features of advantage, some of which with the foregoing, will be set forth in the following description of our invention. It is to be understood that we do not limit ourselves to this disclosure of species of our invention, as we may adopt variant embodiments thereof within the scope of the claims.

Referring to the drawings:

Figure 1 is a vertical sectional view of our tube; and

Figure 2 is a bottom view of the same.

In terms of broad inclusion, our electron tube comprises an evacuated envelope containing concentric electrodes such as a cathode, anode and one or more grids, our improvements relating particularly to the envelope construction and the electrode supporting and terminal structure. As embodied in a tetrode, the envelope preferably comprises two sections sealed together along a plane transverse to the tube axis, with the anode supported by the upper section and the cathode, control grid and screen grid supported by the lower section. The anode supporting lead on the upper section is preferably coaxial with the envelope axis and terminal pins for the other electrodes are preferably arranged on the lower section to lie in a circle about the envelope axis. In our improved tube the lower envelope section comprises a molded vitreous header in which the terminal pins and electrode supports are sealed, conductor means between the pins and supports being preferably sealed within the vitreous header. The cathode support is preferably sealed centrally of the header and the supports for the control grid and screen grid are preferably sealed in circular formation about the cathode support, the grid mounts being preferably of conical shape with legs connected to the respective supports.

2
The anode lead is preferably tubular and communicates with the interior of the envelope to also provide the exhaust tubulation for the tube.

In greater detail and referring to the drawings, our improved electron tube, illustrated as a tetrode, comprises an envelope having an upper section 2 and a lower section 3. The upper section comprises a cup-shaped blank 4 of a vitreous material such as glass having sealed to its lower edge a metal ring 6 provided with an outturned flange 7. The lower section 3 comprises a vitreous header 9 forming the bottom wall of the envelope and has sealed along its periphery a metal ring 11 with an outturned flange 12 registering with flange 7 of the upper section. Header 9 is preferably molded in the desired shape, as by melting powdered glass in a graphite mold. By such molded glass technique the various metal parts hereinafter described may readily be sealed in place during the molding operation. After the tube has been assembled the envelope sections are sealed together by a braze 13 about the periphery of flanges 7 and 12.

In our tube the electrodes are of concentric cylindrical construction comprising a cathode 14, control grid 16, screen grid 17 and anode 18. The cup-shaped metal anode 18 is supported from the upper envelope section 2 by a lead 19 extending coaxially with the axis of the tube. This lead is hollow and serves the dual function of providing a conductor for the anode and an exhaust tubulation for the envelope. Tubular body 21 of the lead is sealed to the upper portion of glass blank 4 and has a suitable fitting 22 at its lower end for fastening to the anode 18. A metallic extension 23 of the lead provides a connection to the exhaust system and, after evacuation of the envelope, is pinched off by compressing the walls of the tubing together at tip 24. Slots 26 in the lead serve to retard heat flow from the anode to the glass seal. This improved anode lead structure removes the complications usually occurring when an exhaust tubulation is arranged at the base portion of the tube. In our tube the absence of such an exhaust tubulation at the base materially simplifies the header structure.

The cathode 14, control grid 16 and screen grid 17 are all mounted on the lower envelope section 3 so that these electrodes may be accurately assembled and aligned prior to the putting on of the upper half of the envelope. Cathode 14 comprises a cylinder of metal such as nickel, preferably cup-shaped, having an electron emissive coating such as the barium-strontium oxide mixture commonly used for that purpose. The

cathode is mounted on a circular support 27 sealed centrally in the header 9, this support being preferably cup-shaped with its lower portions embedded directly in the glass of the header. The flange of support 27 carries a sleeve 28 which in turn is connected to the cathode by an interposed sleeve 29. This latter sleeve is of thin metal having poor heat conductivity so as to thermally isolate the cathode from the header structure. A metal rod 30 connected to the lower end of support 27 preferably projects out through the bottom of header 9 for the purpose of carrying heat out from the cathode supporting structure. This center rod may be used as a cathode terminal, but in our preferred tube construction is used merely as a cooling pin.

Cathode 14 is heated by a suitable heater 31 mounted within the cathode cylinder. This heater is preferably a coil of insulated tungsten wire lying against the inner wall of the cathode, connected at one end to the cathode cylinder and at the other end to a central lead 32. An end plate 33 closing the lower end of the cathode cylinder serves to conserve heat and is insulated from the lead 32 by an insulator bushing 34. Layers of corrugated sheets 36 at the top provide additional heat shielding and are preferably of a metal such as zirconium having gettering or gas-absorbing properties, the upper end of the cathode being preferably recessed to retain these disks.

Control grid 16 and screen grid 17 which surround the cathode are preferably of the cage type, fabricated of suitable wire, and are supported at their lower ends from the header structure. The control grid supports 37, say three in number, are arranged in a circle about the cathode support. These supports are sealed in the header and project upwardly into the envelope to carry the control grid mount 38, the latter being preferably conical in shape and having three legs connected to outturned ends of the supports 37.

In a like manner a plurality of screen grid supports 39 are sealed in the header in a larger circle surrounding the cathode support and spaced alternately with respect to the control grid supports. The conical mount 41 for the screen grid has legs connected to the supports 39, which legs lie between those of the control grid mount. This structure provides a rugged mounting for the grids and reduces the capacitance effects between the grid supports.

Four terminal pins 42, 43, 44 and 45 are sealed in the header to project downwardly from the envelope and are arranged in a circle about the tube axis, the upper ends of these pins being embedded in the glass of the header. The interconnections between the terminal pins and electrode supports are preferably sealed wholly within the glass of the header to further enhance the compactness and ruggedness of the base structure. Thus the cathode pin 42 is connected to the rod 30 by a strap 46, the control grid pin 43 is connected to one of the supports 37 by a strap 47, and the screen grid pin 44 is connected to one of the supports 39 by a strap 48, which straps are embedded in the glass of the header. A post 49 connected to the header pin 45 projects upwardly within the envelope to support the outturned end center rod 32, the latter extending through a slot 51 in cathode supporting sleeve 28.

The various terminal pins and electrode supports which are sealed in the header are preferably molded directly to the glass when the header is formed in the mold. For this purpose

the graphite mold is shaped to hold the ring 11 and other metal parts in proper position. Powdered glass is then poured in the mold and all is brought up to the melting point of the glass in a suitable furnace. After assembly of the anode on the upper envelope section and the remaining electrodes on the header section, the two sections of the envelope are fitted together and brazed at 13 along the abutting flanges.

We claim:

1. An electron tube comprising an envelope having a molded vitreous header at the lower end, concentric electrodes in the envelope including a cathode and grid, a support for the cathode sealed centrally in the header and projecting upwardly into the envelope, and supports for the grid sealed in the header in circular formation about the cathode support and projecting upwardly into the envelope, a conical mount for the grid having diverging end portions connected to said grid supports, terminal pins for the electrodes sealed in the header and projecting downwardly from the envelope, and means connecting the pins to the respective electrode supports.

2. An electron tube comprising an envelope having a molded vitreous header at the lower end, concentric electrodes in the envelope including a cathode and control grid and screen grid, a support for the cathode sealed centrally in the header and projecting upwardly into the envelope, supports for the control grid and screen grid sealed in the header in circular formation about the cathode support and projecting upwardly into the envelope, the circle defined by the screen grid supports being larger than that of the control grid supports, terminal pins for the electrodes sealed in the header and projecting downwardly from the envelope, and means connecting the pins to the respective electrode supports.

3. An electron tube comprising an envelope having a molded vitreous header at the lower end, concentric electrodes in the envelope including a cathode and control grid and screen grid, a support for the cathode sealed centrally in the header and projecting upwardly into the envelope, supports for the control grid and screen grid sealed in the header in circular formation about the cathode support and projecting upwardly into the envelope, the circle defined by the screen grid supports being larger than that of the control grid supports, a conical mount for the control grid having diverging end portions connected to the control grid supports, a conical mount for the screen grid having diverging end portions connected to the screen grid supports, terminal pins for the electrodes sealed in the header and projecting downwardly from the envelope, and means connecting the pins to the respective electrode supports.

4. An electron tube comprising an envelope having a molded vitreous header at the lower end, concentric electrodes in the envelope including a cathode, a support for the cathode comprising a cup having its lower portion sealed centrally in the header, said cup penetrating only partially into the header, and a sleeve connecting the cathode to the flange of said cup.

5. An electron tube comprising an envelope having a molded vitreous header at the lower end, concentric electrodes in the envelope including a cathode and grid, a support for the cathode comprising a cup having its lower portions sealed centrally in the header, a sleeve connecting the

cathode to the flange of said cup, supports for the grid sealed in the header in circular formation about the cathode support and projecting upwardly into the envelope, and a conical mount for the grid having legs connected to said grid supports.

6. An electron tube comprising an envelope having a molded vitreous header at the lower end, concentric electrodes in the envelope including a cathode and control grid and screen grid, a support for the cathode comprising a cup having its lower portion sealed centrally in the header, a sleeve connecting the cathode to the flange of said cup, supports for the control grid and screen grid sealed in the header in circular formation about the cathode support and projecting upwardly into the envelope, a conical mount for the control grid having legs connected to the control grid supports, and a conical mount for the screen grid having legs connected to the screen grid supports.

7. An electron tube comprising an envelope having upper and lower sections, the lower section having a molded vitreous header forming the bottom wall of the envelope, concentric electrodes in the envelope including an anode and cathode and grid, terminal pins and supports for the cathode and grid sealed in the header, and a lead for the anode sealed to the upper envelope section, the anode lead being coaxial with the envelope axis and said cathode and grid terminal pins being located in the circle about said axis, said supports for the grid being located in a circle of different diameter than that of the terminal pins.

8. An electron tube comprising an envelope having a vitreous header at the lower end, concentric electrodes in the envelope including a control grid and screen grid, supports for the control grid and screen grid sealed in the header and projecting upwardly into the envelope, and terminal pins for the electrodes sealed in the header and projecting downwardly from the envelope, said terminal pins and grid supports lying in concentric circles of which the circle defined by the pins is the smallest, the circle defined by the control grid supports is next largest, and the circle defined by the screen grid supports is the largest.

9. An electron tube comprising an envelope having a vitreous upper portion, concentric electrodes in the envelope including an anode, and a tubular metallic lead extending coaxially of the electrodes through the envelope for supporting the anode, the vitreous upper portion of the envelope being fused to the side walls of the tubular anode lead intermediate the ends of said lead, the lead providing a conductor for the anode and also communicating with the interior of the envelope to provide an exhaust tubulation, the outer end of the lead having its side walls compressed together to close the tubulation.

10. An electron tube comprising an envelope having a vitreous upper portion, concentric electrodes in the envelope including an anode, a tubular metallic lead extending coaxially of the

electrodes through the envelope, the anode, the vitreous upper portion of the envelope being fused to the side walls of the tubular anode lead intermediate the ends of said lead,

5 10 15 20 25

the lead providing a conductor for the anode and also communicating with the interior of the envelope to provide an exhaust tubulation, the outer end of the lead having its side walls compressed together to close the tubulation, a cap across the upper end of the anode, and means connecting the anode cap to the inner end of said lead.

11. An electron tube comprising an envelope having upper and lower sections joined together 15 20 25

in a plane transverse to the axis of the envelope, concentric electrodes in the envelope including an anode, a tubular metallic lead perpendicular to said plane and extending through the upper section for supporting the anode, said upper envelope section being connected to the side walls of the tubular anode lead intermediate the ends of said lead, the lead providing a conductor for the anode and also communicating with the interior of the envelope to provide an exhaust tubulation, the outer end of the lead having its side walls compressed together to close the tubulation, and means on the lower envelope section for supporting others of said electrodes.

12. A tetrode comprising an envelope having 30 35 40 45

upper and lower sections joined together in a plane transverse to the envelope, concentric electrodes in the envelope including an anode and cathode and control grid and screen grid, a tubular metallic lead perpendicular to said plane and extending through the upper section for supporting the anode, said upper envelope section being connected to the side walls of the tubular anode lead intermediate the ends of said lead, the lead providing a conductor for the anode and also communicating with the interior of the envelope to provide an exhaust tubulation, the outer end of the lead having its side walls compressed together to close the tubulation, and means on the lower envelope section for supporting the cathode and control grid and screen grid.
